UNITED STATES PATENT OFFICE.

GOTTLOB HONOLD, OF STUTTGART, GERMANY, ASSIGNOR TO THE FIRM OF ROBERT BOSCH, OF STUTTGART, GERMANY, A CORPORATION OF GERMANY.

SIGNAL-HORN.

1,221,859.

Specification of Letters Patent. Patented Apr. 10, 1917.

Application filed April 7, 1915. Serial No. 19,846.

To all whom it may concern:

Be it known that I, GOTTLÖB HONOLD, a subject of the Emperor of Germany, residing at and whose post-office address is Mili-
taerstrasse 4-6, Stuttgart, Germany, have invented certain new and useful Improvements in Signal-Horns; and I do hereby declare the following to be a full, clear, and exact description of the invention, such as

10 will enable others skilled in the art to which it appertains to make and use the same.

Heretofore in employing a vibratile diaphragm to generate air waves for producing sound signals, the controller for effecting 15 the rapid interruption of the flow from the source of power supply to the operating mechanism for vibrating the diaphragm has been fastened to the diaphragm. For instance, in an electromagnetic device of 20 this kind, the diaphragm carried one of the coöperative contacts in the circuit between the battery and the winding of the electromagnet, or the diaphragm carried a lever which vibrated on the diaphragm in response to movements thereof to control the 25 electric circuit. Similarly, in the case of pneumatically operated horns, the controller carried by the vibrating diaphragm is in the from of a valve or the like. In all these 30 cases, the movement of the diaphragm is damped by the controller, either by periodically striking a rigid or yielding abutment forming a circuit contact or valve member, or by the weight and impact of the spring 35 lever mounted on it. The damping action reduces the volume of the sound, or increases the power required for a given volume, and it sometimes produces in addition a discordant sound as a result of the interfering 40 waves generated by the variation of the movement of the diaphragm from free or impeded vibration.

In accordance with my invention, the vibratile diaphragm of the signal horn gives 45 a clear note of large volume with comparatively small expenditure of energy. I obtain this result by removing the power controller from the vibratile diaphragm and producing the rapid vibration of the dia- 50 phragm by means of a controller responding to the wave action set up thereby to periodi-

cally interrupt and establish connections between the source of power supply and the operating mechanism of the diaphragm. Preferably, a horn of suitable form is arranged in suitable relation to the vibratile diaphragm and is tuned to the note of the vibratile diaphragm or to an overtone thereof, while the controller is carried by the horn in suitable relation to the wave set up 55 in the air within the horn. In this way, the vibratile diaphragm produces vibration of the controller of like period and of like phase to thereby maintain the natural period of vibration of the diaphragm during 60 the note emitting period. The controller may, according to my invention, control a valve of a pneumatically operated system, or, as shown hereinafter, it may produce a rapid interruption in the flow of electric 65 current to an electromagnet acting on the vibratile diaphragm to generate the sound 70 waves.

In the accompanying drawings, I show, partly in longitudinal section and partly 75 diagrammatically, the electromagnetically operated type of signal horn, as an example, Figures 1 and 2 illustrating the arrangement with open end horns in which fundamental and the third overtones are used 80 respectively; and Fig. 3 illustrating the arrangement with a closed end horn in which the first overtone is used.

Referring to Fig. 1, the vibratile dia- 85 phragm *a* is held rigidly around its edge and carries an iron armature *b* at its center responsive to magnetic attraction of the electromagnetic core *c* upon excitation by current flowing through the winding *d* from the battery *e*. The horn *g* has one end in 90 proximity to the diaphragm *a*, and is in the form of a hollow cylindrical pipe extending along the axis of the air waves generated by the diaphragm *a*. The controller is fastened in the side wall of the horn and comprises a vibratile member *h* held rigidly 95 around its edge and having an electric contact *i* fastened at its center so as to coöperate with the stationary contact *k*. The circuit connections include the wires *w* and the hand operated switch or push button *f*.

The modification shown in Fig. 2 is simi-

lar to that of Fig. 1, except that a longer horn *g* is used, the third overtone of the note of the horn being in resonance with the note produced by the vibratile diaphragm *a*.

5 The modification shown in Fig. 3 is the preferred form, since by using a closed end horn *g*, as shown, the horn is but half the length of the open end horn for the same note. In the drawings, the horn has a note 10 corresponding to the first overtone of the note produced by the vibratile diaphragm *a*, and the horn is closed at its outer end by the vibratile controller *h* which, as before, carries the electric contact *i* coöperative with 15 the stationary contact *k* in the circuit of the electromagnet winding *d*.

In the drawings, the broken lines *l* represent the stationary waves set up in the column of air in resonance with the waves produced by the vibratile diaphragm *a*. In Fig. 1, the center of the vibratile controller *h* is opposite the node *y* of the wave, and in Fig. 2, the center of the vibratile controller *h* is likewise opposite a node *m* of the wave. 20 25 In Fig. 3, the vibratile controller *h* is placed at a node *m* of the wave, and the controller *h* is located at the end of the pipes since there is a node at this point.

It will be observed that in all cases, the 30 horn *g* is tuned to the vibrations of the air wave *l* so that amplification of the sound volume is secured by resonance of the horn. Furthermore, the central points of the vibratile diaphragm *a* and the vibratile controller *h* are separated along the axis or 35 wave *l* by a distance equal to a multiple of the wave length, these two members vibrating synchronously and remaining in phase during vibration.

40 The operation of the three modifications is the same. Normally, the switch *f* is open and the vibratile controller *h* occupies an unstressed position in which the contacts *i* and *k* are engaged. Upon closing the switch 45 *f*, the vibratile diaphragm *a* is attracted by the electromagnet, which is then excited by current flowing into the winding *d* from the battery *e*, and the air wave generated produces a simultaneous movement of the controller *h* in a direction to separate the contact *i* from the contact *k*. The electric circuit then being open, the vibratile diaphragm *a* springs back to its normal position 50 and the vibratile controller *h* again closes 55 the circuit at the coöperative contacts. The diaphragm *a* is thereupon attracted again, and the vibration thereof continues as long as the switch *f* is held closed, the controller *h* vibrating synchronously, and in phase 60 therewith as a result of the variation of pressure at the node point at which the vibratile controller is located. In this way, the vibratile diaphragm *a* produces with a comparatively small expenditure of energy,

a clear tone which is amplified by the horn 65 to produce a signal of intense volume, suitable for a warning for automobiles, motor boats and analogous purposes.

Having thus described my invention, what I claim is:

70 1. In a signal horn, a vibratile diaphragm, operating mechanism for the diaphragm, a source of power supply, a horn in proximity to the diaphragm, and a vibratile controller carried by the horn and vibrated by air waves generated by the diaphragm, said controller effecting a rapidly interrupted flow from the source of power supply to the operating mechanism.

75 2. In a signal horn, a vibratile diaphragm, operating mechanism for the diaphragm, a source of power supply, a tuned vibratile controller synchronously vibrated by the air waves generated by the diaphragm and effecting a rapidly interrupted flow from the 80 85 source of power supply to the operating mechanism.

80 3. In a signal horn, an electromagnet, a vibratile diaphragm magnetically responsive to the electromagnet, a source of current supply, a horn in proximity to the diaphragm, a vibratile controller carried by the horn and vibrated by air waves generated by the diaphragm, and circuit connections including coöperative disengaging 90 95 contacts one of which is carried by the controller to effect a rapidly interrupted flow from the source of current supply to the winding of the electromagnet.

95 4. In a signal horn, a vibratile diaphragm, operating mechanism for the diaphragm, a source of power supply, a horn having one end in proximity to the diaphragm, and a vibratile controller covering the other end of the horn, said controller being vibrated 100 by air waves generated by the diaphragm and effecting a rapidly interrupted flow from the source of power supply to the operating mechanism.

105 5. In a signal horn, a vibratile diaphragm, operating mechanism for the diaphragm, a source of power supply, a horn in proximity to the diaphragm, and a vibratile controller vibrated by air waves generated by the diaphragm and effecting a rapidly interrupted flow from the source of power supply to the operating mechanism, the controller being 110 115 tuned with the diaphragm and being arranged to interrupt the flow from the source whenever the diaphragm is actuated by the 120 operating mechanism.

115 6. In a signal horn, an electromagnet, a vibratile diaphragm magnetically responsive to the electromagnet, a source of current supply, a horn having an open end in proximity to the diaphragm, and being arranged 125 along the axis of vibration of the diaphragm, a vibratile controller covering the

outer end of the horn and vibrated by air waves generated by the diaphragm, and circuit connections including coöperative contacts one of which is carried by the 5 troller to effect a rapidly interrupted flow from the source of current supply to the winding of the electromagnet.

In testimony whereof I affix my signature.

GOTTLOB HONOLD.
